UNITED STATES PATENT OFFICE.

GEORGE F. HODKINSON, OF PHILADELPHIA, PENNSYLVANIA, ASSIGNOR OF ONE-HALF TO AMERICAN WATER SOFTENER COMPANY, OF PHILADELPHIA, PENNSYLVANIA, A CORPORATION OF NEW JERSEY.

PROPORTIONATE APPLICATION OF CHEMICALS TO FLUIDS.

1,243,737.

Specification of Letters Patent. Patented Oct. 23, 1917.

Application filed May 9, 1912. Serial No. 696,178.

To all whom it may concern:

Be it known that I, GEORGE F. HODKINSON, a citizen of the United States, residing at School Lane and Pulaski avenue, 5 Philadelphia, in the county of Philadelphia and State of Pennsylvania, have invented a certain new and useful Proportionate Application of Chemicals to Fluids; of which the following is a specification.

10 The purpose of my invention is to apply proportionate quantities of a chemical to a fluid being treated and having a variant flow by means which determines the rate of flow by the difference between the heights of 15 bodies of the fluid treated.

A further purpose of my invention is to translate effective head of fluid treated into effective head of treating fluid through 20 mechanism which adjusts to the height of fluid treated upon both sides of a submerged orifice.

Further purposes of my invention will appear from the specification and the claims appended thereto.

25 I prefer to illustrate my invention by a form thereof which I have determined to be practical, efficient and relatively inexpensive and which at the same time well illustrates the principles involved.

30 Figure 1 is a vertical longitudinal section of a preferred form of my invention.

Fig. 2 is a top plan view of the structure shown in Fig. 1 with the roof and a floor removed.

35 Fig. 3 is an enlarged elevation, partly broken, showing a differential connection used in the form illustrated in Fig. 1.

Fig. 4 is an enlarged side elevation of the feeding mechanism for the corrective fluid.

40 In the treatment of water supply, sewage and other liquids to correct for undesirable elements or supply desired constituents, as well as in the mixing of liquids for a great variety of purposes, uniformity of feed of 45 the corrective material in proportion to the need is highly necessary and difficult of attainment. For this reason, in many installations, attempt is made to regulate the feed by hand in proportion to the fluid flow as

50 indicated. I have supplied a method and apparatus which feeds a corrective or additional fluid automatically in proportion to

the need, varying the flow of the second fluid by operation of the same law as controls the flow of the fluid treated or with which the 55 second fluid is mixed.

While the fluid treated may be stored in any character of reservoir, dam, or tank, open or closed and may be delivered to any other suitable reservoir, dam or tank, 60 through a preferably submerged controllable opening, so as to cause the flow through the opening to vary according to the well recognized laws of flow of fluids due to the variant head of fluid in the delivering container, over that in the receiving container, I have preferred to limit the content of both of these chambers for the purpose of better regulating and distributing the application of the treating fluid to the fluid 65 treated and because I can then better protect and mix the fluid during its treatment. Evidently the only requirements as to what I shall hereafter call the treated fluid are that there shall be flow from one body thereof 70 to another with means of converting the effective head causing the flow into preferably proportionate motion for the operation of the feed of what I shall hereafter call the treating fluid. There must, of course, 75 be a division wall where the difference between the heads upon the two sides, i. e., the effective head, is depended upon for the flow.

I prefer to make use of delivery and receiving tanks 2 and 3 and may mix the fluids or treat the treated fluid in either of them at will, in proportion to the flow from one to the other as determined by the difference in heights between the discharge and receiving compartments or the height of water flowing over a weir.

The two tanks or compartments which I prefer to use to secure greater convenience and efficiency are shown as having walls 4 95 and 5, bottom 6 and a top 7, which provides a floor for a regulating table above the tanks. I show inlet pipe 8, and outlet pipe 9, which latter is above any suitable adjustable opening 10 between the two tanks, 100 in order that this opening 10 may always be submerged and the flow through it may consequently follow the law of the flow of liquids through submerged openings.

What I have called tanks may, in fact, contain large or small bodies of the treated fluid in accordance with the needs of the particular installation, whether the operation be treating or more properly mixing and the preference of the designer. They afford opportunity for treatment of the fluid within either of the tanks at will, and, when covered, give protected storage of the water during and subsequent to the treating operation with opportunity for thorough mixing of the treating and treated liquids.

I have applied my invention to fluids flowing through a submerged orifice, where account must be taken of the fluctuating fluid levels upon both sides of the orifice to determine and translate into proper treating fluid feed-regulating movement the effective head obtained.

20 I prefer to use floats, among the various devices available to determine the "heads" or heights of fluid in the two bodies of treated fluid, preferring to take the measurements from the heights rather than from, for example, the variant pressures resulting from these heights, because differences in heights can be measured more delicately and more directly applied to the control of the treating fluid than differences in pressure.

30 The location of the head-determining apparatus is a matter of convenience largely, provided they can be connected with the bodies whose heads are to be compared. I have preferred to place both of the floats 35 11, 12 upon the same side of the division wall and to operate one of them, by connections extending through the wall from the body of fluid farthest distant from it. In order to make this operation effective, I 40 have placed this float 12 within a tube, shell or pipe 13 which has no connection with the discharging body of fluid 14 shown within compartment 2 but which is connected with compartment 3 as by pipe 17 so that the 45 height of the fluid within pipe 13 always corresponds to that of the receiving body 15 of fluid. I have preferred to place the float 11 within a tube, shell or pipe also to protect it from undue influence by the currents 50 of fluid within body 14 with which its interior is connected, however, by openings 16.

The shell 13 is shown as connected with the body of fluid 15 for convenience by a pipe 17 whose end 18 is screened to protect 55 against foreign matter as well as undue variation by reason of fluctuation of the fluid in the body 15. The end 18 is preferably spaced laterally from the submerged aperture 10, so as not to be affected by the 60 fluid passing therethrough.

I have preferred to provide for graduation or adjustment of the size of the opening 10, both in order that a standard apparatus 65 may be put out capable of treating widely variant quantities of flow, and so that ad-

justment may be made as desired from time to time to accommodate or agree with larger or smaller average daily or weekly flows if desired.

I effect this adjustment, in the form illustrated by means of a slidable plate or gate 19, which I place upon the delivery side of the aperture in order that the flow or tendency to flow may press it against the wall within which the aperture is made. Having a larger surface exposed upon the delivery side than is exposed where it passes the aperture, the tendency would be to press this gate against the division wall between the two bodies of treated fluid, even when the heads on the two sides of the division wall are approximately equal. This would still be true even if that on the receiving side slightly exceeded that upon the delivery side.

85 I prefer to guide the gate 19, as at 20, and to operate it, by means of a rod 21, from any suitable standard 22, as by wheel 23 and appropriate intermediate mechanism. The position of the gate may be conveniently shown by arrow 24, movable along scale 25.

90 By this gate construction the size of the aperture 10 is adjusted to accommodate an estimated or known mean rate of flow and the height of division wall is made to correspond with the limit of possible backing up of flow during the times of maximum rate thereof, or, safely, with the height of the source from which the fluid treated is supplied.

95 Proper treatment by my mechanism and method does not require knowledge of the exact rate of flow. The quantity of chemical, for example, supplied can be adjusted until the fluid treated passes the required test, setting the device without knowledge of either the rate or quantity of flow of treated fluid.

100 In the illustration which I have given, where the one fluid is being "treated" by the other, rather than "mixed" with another, the quantity of flow of the second fluid is necessarily relatively small. I have therefore illustrated connections and container for the treating fluid as well as regulation 105 therefor which are arranged upon a relatively small scale. It will be well understood by those familiar with the art that any desired quantity of treating fluid or fluid to be mixed with another, may be handled in 110 accordance with the principles of my invention disclosed herein, without involving further invention.

115 In the illustration I supply the treating fluid within either body of treated fluid at 125 will by means of pipes 26 and 27, which are connected to a common supply pipe, 28, and are controlled by means of valves 29, and 30, from hand operating means 31 and 32. I have shown the connection as by cords or 120

chains 33 and 34, and may connect the valves in any suitable manner, if desired, to automatically close one of the valves as the other is opened. The connection which I have illustrated for this purpose is through a cord or chain 35 controlling their operating devices. I prefer to terminate the pipes 26 and 27, as at 38 and 39, in proximity to and preferably nearly in line with the aperture 10 in order that the treated fluid may more thoroughly mix with the treating fluid because of the better circulation of treated fluid close to the aperture.

The fluid mixed and which is to be fed into the so-called "treated" fluid is shown, for convenience, as passing from the tanks 40 and 41 to solution tanks 44 and 45 by means of pipes 46, 47 controlled by valves, as 48 or 49, if desired. By the duplicate arrangement of mixing and solution tanks which I have shown I am enabled to draw freely from one set while fluid is being prepared or is stored in the other.

I pass the fluid from tank 44 or 45 into what I will term a "feed" tank 50, through valve 51, whose fluid level is maintained preferably by float actuation in order that I need not adjust or vary the movement of my feeding mechanism to adjust for variation in fluid level.

My invention concerns particularly the translation of variation in the effective head of the one fluid, here determined by relative movement of the floats 11 and 12, into proportionate variation in the rate of feed of another fluid, here the fluid within the tank 50, fed down through pipe 28. In the construction shown I accomplish this by proportionate alteration of the depth of submergence of the discharge aperture beneath the surface of fluid in tank 50.

In the illustration I accomplish this proportionate variation by applying the same law to the feeding of the "treating" fluid as causes the variation in flow of the "treated" fluid.

I connect the two floats 11 and 12, by means of chains 52 and 53, counter-weighted at 52', 53', with pulleys 54 and 55, comprising opposite parts of any suitable differential mechanism. The form illustrated is best seen in Fig. 3. The pulleys are secured to sleeves 56 and 57, upon which are mounted gears 58 and 59 engaging upon opposite sides with two gears 60 and 61.

The gears 60 and 61 are retained upon stub shafts 62, 62' by means of collars 63. The shafts 62, 62' are connected with shaft 64 as by any suitable bearing block 65, forming a familiar form of planetary gearing wherein movement of the gears 58 and 59, (in opposite directions angularly) at the same rate of speed, does not affect the position of the stub shafts 62, 62', since the gears 60 and 61 merely rotate upon them.

This is the condition when the floats 11 and 12, are moving upwardly or downwardly at the same rates of speed.

When there is any difference in the extent of rise or fall of the floats 11 or 12, or in their direction of movement, corresponding to a change in relative fluid levels in the two bodies 14 and 15, the stub shafts 62 and 62' will be turned about the shaft 64 in one direction or the other, according to the approach or recession of the two levels, to or from each other and will carry the shaft 64 with them resulting in rotation of the pulley 66.

Within the tank 50 I anchor a device 67 containing any suitable joint, permitting relative movement of the character preferred by the designer without interfering with the flow of fluid through the joint. My preferred construction is best shown in Fig. 4, where the upper end of the pipe 28 is shown as threaded at 68, for engagement with a nut 69 upon the lower side of the bottom 70 of the tank and with a boss or flange 71, upon the upper side of this tank bottom. The boss 71 may represent any suitable fitting within which the pipe 28, is screwed at its upper end, and preferably carries a preferably right angular extension 72 whose interior is in fluid connection with the interior of the pipe 28. Within this extension 72 I pivot the preferably right angular mating extension of a hollow fitting 73 which is connected with a pipe 74 so that the interior of the pipe 74 and any suitable aperture or opening 75 therein, is at all times in fluid connection with the pipe 28, while capable of a swinging movement about the extension 72.

Preferably at the end of the pipe 74, since the aperture preferred by me is in the side thereof, I form any suitable attachment 76 for a cord or chain 77 which passes about the pulley 66, so that rotation of the shaft 64, because of variation in levels of the bodies 14 and 15, results in raising or lowering the aperture and correspondingly varying the depth of submergence of the aperture beneath the level of fluid in tank 50.

It will be evident that other means of varying the rate of flow of the "treating" fluid might be substituted, while obtaining a part of the advantage of my invention though I prefer to vary the depth of submergence of a submerged aperture rather than the height of the fluid or of an opening over which the fluid flows, and that much of the advantage of my invention would be secured by proportionate variation in fluid feed, however secured.

In order that the volume of flow of the "treating" fluid may be controllable, I arrange to adjust the size of the aperture or opening within the member 74, preferably

by adjusting the length of a slot therein, and do this conveniently, in the construction shown, by a sleeve 78, threaded upon the member 74 as at 79. The lock-nut 80 5 may be used if desired.

In operation:—The aperture 10 is opened to the desired extent for the expected mean flow by operation of the gate 20, and the size of the aperture 75 is adjusted to correspond with the flow required for the 10 strength of the "treating" solution available or desired. The size of wheel 66 is selected to provide a rate of variation in submergence corresponding to the variation in 15 level difference between bodies 14 and 15, as transmitted through floats 11 and 12, and the differential intermediate connections. The tank 50 is supplied with treating fluid, and the member 74 is set with the aperture 20 75 just at the level of the fluid in tank 50, when the levels of bodies 14 and 15, are equal, so that flow through the aperture will begin with any relative reduction in the 25 height of the fluid at 15 with respect to that in 14. Valve 29 or 30 is then opened.

Any change in level of the bodies 14 and 15 results in difference in rate of speed of the gears 58 and 59 with corresponding rotation of shaft 64 and movement of the member 74. The operation is automatic and the 30 difference in effective head of fluid upon the effective aperture at 10 is translated into difference of effective head above the aperture 74, in the "treating" solution.

It will be evident that it is not necessary 35 to have anything like the extent of difference in the actual effective heads within the "treating" fluid which exists as actual effective head within the "treated" fluid, though the proportion between the heads 40 effective in causing the flow of the two fluids should be maintained.

It will be evident that even if the structure selected for illustration only be used 45 it may be greatly varied in details and that widely different structures may be used to secure the advantages of my invention without departing from the spirit and scope thereof.

Having thus described my invention, what 50 I claim as new and desire to secure by Letters Patent is:—

1. In an apparatus for treating liquids, a 55 division wall dividing two bodies of the same liquid in a substantially static condition, said wall having a submerged orifice, two floats, one controlled by the height of the liquid in each of the bodies, connections from the floats, a shaft, differential mechanism connected to the shaft and to the floats 60 turning the shaft with relative movement of the floats and maintaining the shaft in stationary position when the floats are sta-

tionary or moving at the same rate and in the same direction, means for feeding the 65 treating medium and connections from the shaft to said means, automatically varying the feed of the treating medium in proportion to variation in effective head between the two bodies of the liquids. 70

2. In a device for treating liquids, a division wall between two bodies of the same liquid in a substantially static condition, said wall having a submerged orifice, floats, one in each body, varying in height with the height 75 of liquid in the two bodies thereof, a tank for the treating liquid, feed mechanism for the feeding liquid having an aperture and means connected with the floats for varying the head of treating fluid effective upon the 80 aperture, with relative movement between the floats.

3. In a low head liquid-treating apparatus, a division wall dividing bodies of the same liquid having their surfaces in substantially static condition, said wall having a submerged orifice, a cut-off for varying the extent of opening of said orifice, floats in the two bodies of liquid and automatic fluid treating mechanism controlled by the relative heights of the floats due to variation in relative heights of liquid in said two bodies. 90

4. In a device for treating liquids, a division wall dividing two bodies of the same liquid in a substantially static condition, said wall having a submerged orifice, a float resting in each of said bodies, differential mechanism transmitting relative vertical movement of the two floats into 100 motion and feeding mechanism for a treating liquid proportioning the feed according to the extent of said motion.

5. In a device for treating liquids, a division wall dividing relatively large bodies 105 of liquids being treated and having a submerged aperture, means for varying the size of the aperture in proportion to the normal rate of flow of the liquid into one of the bodies, floats resting in the two bodies respectively, a container for treating liquid, connections from the container to one of the bodies of liquid to permit flow therebetween, said connections having an inlet from the container capable of variation in depth below the surface thereof and differential means between the floats and the inlet to vary the depth of said inlet below the surface in the container in proportion to the difference in extent of vertical movement of 110 the two floats. 115
